UNITED STATES PATENT OFFICE.

GEORGE W. RAULS, OF CINCINNATI, OHIO.

EXCAVATOR AND LOADER APPARATUS.

1,116,843.

Specification of Letters Patent. Patented Nov. 10, 1914.

Application filed June 17, 1913. Serial No. 774,211.

To all whom it may concern:

Be it known that I, GEORGE W. RAULS, a citizen of the United States of America, residing at Cincinnati, in the county of 5 Hamilton and State of Ohio, have invented certain new and useful Improvements in Excavator and Loader Apparatus, of which the following is a specification, reference being had therein to the accompanying 10 drawing.

This invention relates to an excavating machine and the principal object of the device is the production of a pivoted engine cradle whereby the engine may be supported 15 adjacent the digging and dumping portions of the device, but which may be easily removed by the operation of the engine cradle when it is desired to transport the excavating machine.

20 Another object of the invention is to provide an improved support for operating the scoop.

Another object of the invention is to so construct the excavating machine that it 25 may be conveniently transported from one place to another.

With these and other objects in view, this invention consists of certain novel combinations, constructions and arrangements of 30 parts as will be hereinafter fully described and claimed.

This invention is illustrated in the accompanying drawing, wherein:

Figure 1 is a side elevation of the excavator with the inclined plane in an extended position. Fig. 2 is a side elevation of the excavator with the inclined plane in a folded position and with the engine removed from its support. Fig. 3 is an enlarged side elevation of a portion of the inclined plane in the position shown in Fig. 2. Fig. 4 is an enlarged fragmentary plan view showing the inclined plane in an extended position. Fig. 5 is a longitudinal section through the rear 45 portion of the excavator. Fig. 6 is an enlarged sectional view of the lower end portion of the inclined plane with the scoop at the lower end of the inclined plane.

Referring to the accompanying drawing, 50 it will be seen that this invention comprises a frame provided with supporting wheels and carrying an engine cradle upon which the engine is mounted.

It also comprises an incline plane leading 55 to a tilting platform so that a scoop may be drawn up the inclined plane onto the plat-

form and tilt the same to cause the dirt in the scoop to be dumped into a wagon positioned beneath the platform.

When constructing this frame the platforms 10 and 11 are first built and are then connected with the support for the tilting platform which will be hereinafter described. Each of these platforms 10 and 11, which I shall call the supporting platforms, 60 comprises the side beams 13 having their ends connected by the cross-bars 14 and connected intermediate their length by the bracing bars 15 which carry the bearing blocks 16. Trucks 17 are positioned beneath the 65 platforms 10 and 11 and are pivotally connected with the platforms by the king bolts 18 which pass through the bearing blocks 16 into the bearing blocks 19. Each of these trucks comprises a side bar 20 which are 70 connected at their ends by the cross-bars 21 and intermediate their lengths by the primary section of the bracing bars 22 supporting the bearing blocks 19. The wheels 23 are 75 carried by axles 24 which axles pass through bolsters 25 secured to the side bars 20 supporting the cross-bars 26.

The forward platform 10 carries the rear supporting standards 27 which are connected with the shorter forward supporting 80 standards 28 by the connecting bars 29. These standards 27 and 28 carry the cross-bars 30 upon which the inner end portion 31 of the inclined plane is rigidly secured, as shown in Fig. 5^a. Longitudinally extending 85 guiding strips 32 are secured to the inner end portion 31 of the primary section of the inclined plane converge to guide the scoop and cause it to leave the inclined plane at the proper point.

The rear platform 11 carries the vertical standards 33 and 34 which standards are braced by the cross-bars 35. Additional braces 36 are provided for the standards 33 to prevent the standards 33 from moving out 90 of the vertical position. It should be noted that the standards 34 together with the cross-bars 35 and diagonal braces 36 form a rectangular support which is hinged to the platform 11 by means of the hinges 37 95 so that the engine cradle may be releasably held in a raised position.

The engine cradle comprises longitudinally extending side bars 38 pivotally connected with the standards 33 by means of 100 the bolts 39 and connected by means of the cross-bars 40 positioned at points through-

cut their length. A flooring 41 is built upon the frame formed from the longitudinally extending side-bars 38 and cross-bars 40 and carries a bed 42 for the engine indicated in 5 general at 43. Side rails 44 are provided to prevent danger of persons falling from the cradle. The rectangular support is held in a raised position by the securing pin 45, which is passed through one of the flooring boards into the upper bracing bar 35 of the hinged rectangular support. From an inspection of Fig. 5 it will readily be seen that the hinged support holds the cradle in an elevated position when the excavator is in 10 use, but when the pin 45 is removed that the cradle may be lowered to the dotted line position shown so that the engine may be removed if desired.

The upper platform connects the cross-bars 30 and 35 and comprises the longitudinally extending side bars 46 which are connected by the cross-bars 47 and flooring 48. This flooring 48 is only provided at the rear portion of the upper platform, thus leaving 20 an opening in the forward portion in which opening the tilting platform, before referred to, is mounted. Diagonal braces 49 lead from the cross-bars 14 of the platform 11 to the rear bracing bar 47 of the upper platform, thus strengthening the frame and forming guides to prevent the cradle from moving transversely, when being raised or lowered. The upper platform is also braced by the diagonal braces 49' and 49'.

25 Standards 50 extend from the upper platform and are connected by the shafts 51 upon which the pulley wheels 52 are mounted. These standards 50 are braced by the diagonal bars 53 which bars have their lower ends secured to the cross-bars 54 and form supports for the inclined board 55. This board 55 together with the inclined side boards 56 form a hopper extending about three sides of the opening in which the tilting platform is pivotally mounted. The tilting platform 57 is pivotally mounted in the opening formed in the upper platform and has its forward end resting upon a supporting shaft 58 when in a normal position. 40 This platform is so mounted that it will normally remain in the position shown in Fig. 5, but may be easily tilted when the scoop of dirt rests upon the platform. An abutment strip 59 is positioned beneath the tilting platform to limit the pivotal movement. At the forward end of the tilting platform there are provided curved prongs 60 extending above the upper surface of the platform to steady the scoop and prevent the scoop 45 to steady the scoop and prevent the scoop from sliding from the platform.

The upper portion of the auxiliary section of the inclined plane is hinged to the lower end portion of the primary section and comprises the flooring 61 which is pivotally connected with the side bars 31 by means of

the hinge strips 62 and 63, which strips are secured to the lower and upper portions of the primary and auxiliary sections of the inclined plane and pivotally connected together, as shown in Figs. 3 and 4. This 50 flooring 61 is braced by the cross-bars 64 which bars are connected by the truss-rod 65. Guiding shoes 66 are secured to the lower end portion of the flooring 61 and are provided with downwardly curved points 75 67 which dig into the ground, as shown in Fig. 6, and prevent the edge of the scoop from catching as the scoop starts up the inclined plane. This scoop 68 is of the usual type used in excavating and is provided 80 with the forward and rear yokes 69 and 70 which yokes are pivotally connected with the rear and forward end portions of the scoop so that the scoop may be connected with the ends of the line 71. This line 71 85 passes around a pulley wheel 72 carried by a stake 73 and after passing over the pulley wheels 52 passes around the drum 74 of the engine.

When this device is to be transported to 90 the place where it is to be used, the engine is removed from the cradle and the auxiliary section of the inclined plane is folded as shown in Fig. 2. The forward and rear trucks are connected by the coupling shaft 95 75 at which time the device may be moved to any desired position. When the machine reaches a place where it is to be used, the coupling 75 is removed and after the cradle has been lowered to the dotted line position 100 shown at Fig. 5^b, the engine is then put in place and the cradle raised to the elevated position. The auxiliary section of the inclined plane is then lowered to the position shown in Fig. 1 with the points of the shoes 105 digging into the ground and the line 71 is then passed over the pulley wheels 52, and after one end portion has been passed around the pulley wheel 72 carried by the stake 73 the ends of the lines are connected 110 with the yokes 69 and 70.

The excavator is now ready for operation, and when the engine is started, the scoop will be dragged along the ground toward the inclined plane. As the scoop passes along 115 the ground it is tilted so that the dirt will be scooped up into the scoop until the auxiliary section of the scoop rests on the inclined plane. When the forward edges of the scoop strike the guiding shoes 66, the scoop 120 will be caused to ride on to the inclined plane, and will then travel on this plane until it reaches the upper platform. As soon as the scoop reaches the upper platform 125 it will ride to the tilting platform and the engine is then stopped. The line 71 is slack enough to permit the tilting platform to tilt under the weight of the scoop of dirt so that the dirt will run out of the scoop and into the wagon 77 positioned beneath 130

the upper platform. When the tilting platform tilts, the hopper built around the opening formed in the upper platform prevents the dirt from being thrown from the scoop 5 upon the upper platform. It will thus be seen that the dirt will not gather upon this upper platform and make it necessary for a workman to climb onto the platform and shovel the dirt from the platform in the 10 opening into the wagon. As soon as the scoop is emptied, the engine is started to rotate the drum in the opposite direction from that in which it rotated when bringing the scoop up the inclined plane, and this will 15 cause the scoop to be carried down the inclined plane to the bottom where it can be again filled with dirt. As soon as the scoop leaves the tilting platform, this platform will return to its normal position, shown in 20 full lines in Fig. 5.

What I claim, is:

1. In a device of the class described, the combination with a supporting truck, supporting standards extending upwardly from 25 said truck and adapted to carry at their upper ends an operating mechanism, an engine cradle pivotally secured to said standards intermediate their ends, said cradle adapted to support an engine whereby an 30 engine may be supported adjacent the operating mechanism, and a rectangular supporting frame pivotally secured to said truck adjacent the free end of said cradle, said rectangular supporting frame adapted to be 35 swung to a vertical position for releasably holding said cradle in a horizontal plane, said frame fitting entirely across the lower portion of said cradle for bracing the same, the free end of said cradle adapted to be 40 swung downwardly to a position adjacent the ground when said frame is swung downwardly.

2. In a device of the class described, the combination with a supporting truck, supporting standards extending upwardly from 45 said truck and adapted to carry at their upper ends an operating mechanism, an en-

gine cradle pivotally secured to said standards intermediate their ends, said cradle adapted to support an engine whereby an 50 engine may be supported adjacent the operating mechanism, and a rectangular supporting frame pivotally secured to said truck adjacent the free end of said cradle, said rectangular supporting frame adapted to be 55 swung to a vertical position for releasably holding said cradle in a horizontal plane, said frame fitting entirely across the lower portion of said cradle for bracing the same, and a pin passing through the lower 60 portion of said cradle and engaging said rectangular frame for holding said frame in a vertical position, said rectangular frame adapted to be swung downwardly for allowing 65 an engine to be removed therefrom.

3. In a device of the class described, the combination with a supporting truck, supporting standards extending upwardly from said truck and adapted to carry at their upper ends an operating mechanism, an engine 70 cradle, said cradle having a pair of side-bars, said bars pivotally secured to said standards intermediate their ends, said side-bars adapted to carry a flooring for supporting an engine, a rectangular supporting frame 75 pivotally secured to said truck, said rectangular frame comprising short vertical standards, braces connecting said last-mentioned standards, said rectangular frame adapted to support said engine cradle in a 80 horizontal plane, said short vertical standards fitting under and supporting said side-bars, whereby the weight of said cradle will be directly imparted to said truck by said short vertical standards, the free end of said 85 cradle adapted to be swung downwardly when desired for removing an engine from said cradle.

In testimony whereof I hereunto affix my signature in presence of two witnesses.

GEORGE W. RAULS.
